ABRASIVE DEVICE

Joseph L. Ballash, Cleveland, Ohio, assignor to
 The Sterling Grinding Wheel Company, Tiffin,
 Ohio, a corporation of Ohio

Application November 16, 1936, Serial No. 110,985

4 Claims. (Cl. 51—209)

This invention relates to an abrasive device of the type comprising an annular chuck and a segmental grinding ring held therein. The invention has reference particularly to improved 5 means for clamping and holding the segments in place in the chuck.

In an abrasive device or grinding wheel of the type herein contemplated, the segments are clamped in place by an externally tapered 10 clamping ring which brings the contiguous edges of the segments into tight clamping engagement with one another and thereby necessarily contracts the segmental ring. The foregoing construction in itself provides an effective clamping 15 means, but, according to the provisions of the present invention, this means is augmented by an internal support for the upper ends of the segments in the form of an internal flange or shoulder, having a slight clearance between it and the inside of the wheel. The clearance between the internal segment support and the 20 wheel allows the adjacent edges of the segments to be brought in tight clamping engagement with each other in the normal manner but prevents or limits the spreading or flaring of the 25 outer ends of the segments under the action of centrifugal force. This clearance between the internal supports for the segments and the wheel proper fills up with abrasive material during 30 operation of the device which tends to decrease the clearance and better support the segments.

The object of the invention is, therefore, to provide an abrasive device or grinding wheel of 35 the type above mentioned wherein an improved, novel, and exceedingly effective clamping or holding action on the segments is obtained.

The invention may be further briefly summarized as consisting in certain novel details of 40 construction and combinations and arrangements of parts which will be described in the specification and set forth in the appended claims.

In the accompanying sheet of drawings showing 45 the preferred embodiment of the invention and certain slight modifications,

Fig. 1 is a side elevation of an abrasive device embodying the present invention, comprising a 50 chuck and a segmental ring type abrasive member;

Fig. 2 is a bottom view of the abrasive device shown in Fig. 1;

Fig. 3 is a section on the line 3—3 of Fig. 2;

Fig. 4 is a section similar to Fig. 3 but showing 55 a modified construction;

Fig. 5 is a fragmentary perspective view of the chuck shown in Figs. 1, 2, and 3, showing a different form of abrasive member secured therein; and

Fig. 6 is a fragmentary view similar to Fig. 2, showing a still further form of abrasive member.

The present invention is especially applicable to surface grinders of the type comprising a vertical spindle to the lower end of which is secured 10 an abrasive device including a chuck or holder 15 and an abrasive member, in this instance a segmental abrasive ring, secured in the chuck and projecting from the lower side thereof.

Referring now to the drawing, 10 represents the body of the chuck which is designed to be secured to the lower end of the rotating spindle of the grinder in this instance by bolts adapted to engage in tappet holes 11 which are provided in an elevated part of the chuck body somewhat near its inner periphery, the chuck body being generally in the form of an annulus the cross-section of which is indicated in Fig. 3. Additionally, the abrasive device includes an abrasive member in the form of a segmental ring wheel or annulus 12 the upper part of which 20 extends into the lower side of the chuck and is clamped therein. The adjacent segments are in engagement with each other at least for a portion of their depth, preferably the full depth, and their edges are preferably interlocked by a 25 tongue and groove construction shown at 12b in Figs. 1 and 2, wherein the segments are designated 12a. That is to say, each segment has on one upright edge a groove and on its opposite edge a tongue, and when the segments are assembled in the chuck and are clamped in place, the tongue of one segment engages the base of the groove of the adjacent segment, but preferably inwardly and outwardly of the engaging portions clearances are provided between the 30 segments which are therefore generally of the construction constituting the subject matter of my Patent No. 1,714,754. The inner and outer surfaces of the segments are arcuate and, in fact, 35 concentric so that the segmental abrasive ring 40 is in effect a cylindrical section. The tongue and groove interlocking segment construction is not 45 essential to the invention, however, as will appear presently.

The chuck body 10 is provided on its lower 50 side with a channel which receives and in which is clamped the upper portion of the segmental abrasive wheel 12, this channel being formed by an inner annular flange 13 and an outer annular flange 14 concentric therewith. The 55

flanges 13 and 14 may both be integral with the chuck body, as shown in Fig. 3, but either or both may be separate members attached to the body of the chuck. Generally, the outer flange 14 is integral, but in some instances the inner flange is a separate member secured to the chuck body, as shown at 13a in Fig. 4, which shows the inner flange formed as a part of an annular angle member 15 secured to the chuck body by screws or bolts 16. The constructions shown in Figs. 3 and 4 are otherwise similar.

The surface of the flange 13 or 13a adjacent the abrasive wheel is cylindrical and a small clearance is provided between the same and the inside diameter of the abrasive wheel. The inner surface of the outer flange 14 is tapered to accommodate an outer tapered split clamping ring 17, the inner cylindrical surface of the clamping ring 17 engaging the outer arcuate surfaces of the segments. The split clamping ring 17 is designed to be drawn inwardly to clamp the segments in place by bolts 18 which have threaded engagement with the clamping ring and pass through openings in the chuck body, the openings being large enough to provide clearance for the shanks of the bolts as they move laterally inwardly slightly when the bolts are tightened, i. e., during the clamping operation.

In assembly, the segmental abrasive ring 12 is placed in the channel of the chuck between the inner flange 13 (or 13a) and the outer split clamping ring 17. Then the clamp 17 is drawn inward by turning the bolts 18, contracting the segmental ring 12 and causing the edges of the segments to be drawn into tight clamping engagement. This in itself causes a clamping or holding action in the chuck body, but I find that a still more effective holding action is obtained by the provision of the inner flange or wall 13 or 13a. The annular surface of the inner flange is so positioned with reference to the segmental abrasive ring 12 (taking into consideration the diameter of the inner surface of the abrasive ring 12 at the time the segments are brought into tight clamping engagement when the wheel is being contracted by the split clamping ring 17) that it does not interfere with the normal clamping of the segments, which when brought into clamping engagement with one another by the contraction of the ring have a slight clearance 19 of about $\frac{1}{32}$ " with the inner annular wall 13 or 13a. Particularly does the inner wall prevent the lower or working ends of the segments from spreading or fanning laterally outwardly under the action of centrifugal force and all danger of disruption or "explosion" of the wheel in operation is prevented. The accumulation of abrasive material worn from the wheel during operation in the clearance 19 has a tendency to decrease the clearance between the inner wall 13 or 13a and the inside of the abrasive wheel. This decreases the clearance, more securely clamps the segments in the chuck, and assists in preventing the outer ends of the segments from flaring laterally outward during operation.

The clearance between the grinding ring and the internal flange of the chuck should be kept as small as practical without having the internal flange interfere with the initial clamping of the segments and in no event should it greatly exceed $\frac{1}{32}$ ". If the groove between the grinding ring and the internal flange of the chuck is too wide the purpose of providing the flange is de-

feated as it will not adequately prevent the segments from flaring in operation.

As previously stated, the full depth engagement of the edges of the adjacent segments is not essential nor is the interlocking or tongue and groove construction of the segments necessary. In Fig. 5 I have shown a gap type segment abrasive ring with the segments designated 12c spaced apart as indicated at 12d below the chuck. At or in the vicinity of the chuck the segments widen out and are in engagement with each other so that the clamping effect produced by the contraction of the ring will be obtained as before.

In Fig. 6 I have shown a segmental abrasive wheel wherein the segments, here designated 12e, have flat engaging edges 12f. As here illustrated, the segments engage on nonradial lines, but the engagement may be on radial lines if desired. This figure also shows the segments 20 abutting tight against one another but it is to be understood that a slight clearance therebetween might be provided at the lower ends of the segments so long as there is sufficient bearing at the upper ends of the segments for clamp- 25 ing purposes.

While I have illustrated certain embodiments of the invention, it will be apparent that other changes may be made in details of the segments and of the chuck, and I therefore aim in my 30 claims to cover all modifications which do not involve a departure from the spirit and scope of my invention.

Having thus described my invention, I claim:

1. An abrasive device comprising a chuck and a segmental grinding ring, the segments having edge portions in engagement with one another, the chuck having means located exteriorly of the segments for contracting the ring and thus forcing the edges of the segments in tight clamping engagement with one another, and an inner wall spaced from said grinding ring but adjacent thereto forming a narrow groove not greater than about $\frac{1}{32}$ " wide within which particles worn from the wheel are adapted to accumulate 40 and prevent spreading or flaring of the segments during operation.

2. An abrasive device comprising a segmental abrasive ring, an annular chuck having tapered clamping means surrounding the segments and serving to contract the ring and thus cause clamping engagement between the engaging edges of the segments, and an inner wall adjacent said abrasive wheel but having a slight clearance therewith forming a groove about $\frac{1}{32}$ " wide adapted to collect particles worn from the wheel and prevent tilting of said segments about the clamping means and spreading or flaring of the wheel during operation.

3. An abrasive device comprising an annular chuck having a channel formed on one side thereof including two opposed surfaces the inner being cylindrical and the outer being tapered, a segmental abrasive ring composed of segments having their adjacent edges in contact with one another extending into the channel in spaced relation to the inner cylindrical surface, and a split clamping ring located in the channel exteriorly of the segments and in engagement therewith and having a tapered surface in engagement with the tapered surface of the chuck channel, and means for adjusting the clamping ring, said inner cylindrical wall being adjacent the inside of the abrasive ring but slightly spaced therefrom forming a groove about $\frac{1}{32}$ " wide with- 75

in which particles worn from the wheel are adapted to accumulate and prevent spreading or flaring of the segments without interfering with the clamping of the segments by the split clamping ring.

4. A chuck for a segmental grinding wheel comprising a chuck body having on one side thereof a channel composed of a base and two opposed lateral walls, the inner wall having a 5 cylindrical surface of slightly less diameter than the internal diameter of the wheel with which

the chuck is to be used and adapted to form therewith a narrow deep groove not greater than about $\frac{1}{16}$ " wide within which particles worn from the wheel are adapted to accumulate, and the outer wall having a tapered surface, a split 5 clamping ring having a tapered surface engageable with the tapered surface of the chuck, and bolts engaging the chuck and the clamping ring for adjusting the latter.
